UNITED STATES PATENT OFFICE.

JOSEPH ANDERSON, OF PITTSBURG, PENNSYLVANIA.

STEAM-BOILER FURNACE.

SPECIFICATION forming part of Letters Patent No. 360,079, dated March 29, 1887.

Application filed December 10, 1884. Serial No. 149,939. (No model.)

To all whom it may concern:

Be it known that I, JOSEPH ANDERSON, of the city of Pittsburgh, in the county of Allegheny and State of Pennsylvania, have invented a new and useful Improvement in Steam-Boiler Furnaces; and I do hereby declare the following to be a full, clear, and exact description thereof, reference being had to the accompanying drawings, in which—

10 Figure 1 is a side elevation of a steam-boiler, partly in section, illustrating my improvement. Fig. 2 is a sectional plan view on the line $x-x$ of Fig. 1. Fig. 3 is a front elevation of Fig. 1, the latter being a vertical longitudinal section on the line $z-z$ of this figure.

Like letters of reference indicate like parts. My improvement relates to the construction and arrangement of a furnace in which the air for supporting combustion is heated by the 20 products of combustion from the furnace before it is introduced into the fire-chamber.

I will now describe my invention with reference to a furnace in which gaseous fuel is used; but it applies equally to every description 25 of furnace, whatever kind of fuel it may be adapted to, whether gaseous or solid.

In the drawings, a represents steam-boilers of the usual construction having the ordinary longitudinal flues, $b b$. The gas is introduced 30 into a closed chamber, c , through a perforated T-burner, d , arranged therein, and deriving its gas from a supply-pipe, d' , which enters the wall of the chamber. The gas ignites in this chamber, and the burning gas and heated 35 products pass over the bridge-wall e , along the bottom of the boiler to its rear end, thence back again through the flues $b b$ to the stack f .

Above the boilers is a chamber, h , which extends the entire length of the boilers, and is 40 preferably made with brick walls, as shown in the drawings. Within the chamber is a flue, $i i'$, which enters at the front end and extends to the rear, where it is reflexed, and extends again to and outside of the front end of the 45 chamber. Both ends of the flue $i i'$ are open and communicate with the stack, the lower branch, i , communicating with the chamber f' , which is formed by the usual stack-skirt, which receives the smoke from the boiler-flues, and 50 the upper branch, i' , communicating with the stack proper, f . A partition, f^2 , is arranged

in the stack between the openings of the branches $i i'$ of the flue, so as to shut off all direct communication between the skirt-chamber and the rest of the stack. The heated 55 products of combustion from the boiler-flues $b b$, after passing into the chamber f' , are thus obliged to enter the mouth of the flue $i i'$, and to pass therethrough in a circuitous course to the stack f above the partition f^2 . In their 60 passage they raise the flue and the surrounding air in the chamber h to a considerable degree of heat.

The chamber h is closed, except that at the rear end is an air port or opening, h' , and at 65 the side of the chamber, near the front end, is another opening, from which a pipe, h^2 , leads to the combustion-chamber c , the outlet of the pipe h^2 being just underneath the gas-burner d .

The combustion-chamber is closed, so that 70 all the air for combustion of the gas must be drawn from the air-chamber h through the pipe h^2 . The air thus removed from the chamber h is supplied by air entering the opening h' , and in this manner there is a continuous 75 circulation of air through this chamber around the flue-pipes $i i'$ and down the pipe h^2 to the combustion-chamber. The contact with the flue $i i'$, and with the surface of the boiler within the chamber, is sufficient to heat the air enough 80 to economize fuel and to increase the capacity of the furnace very largely.

In addition to utilizing the waste products of the furnace for heating the air, an advantage 85 of my improvement is that the chamber h acts as a non-conducting covering for the boiler, because it is in juxtaposition to the top thereof, and is continually filled with heated air.

In case of the application of my improvement to a battery of more than one boiler the 90 chamber h may be made to cover all the boilers, or there may be a separate chamber for each boiler, as desirable. In either case the most convenient way of constructing the chamber is to extend the brick walls m of the boiler 95 structure upward to the required distance above the boiler level, connecting them by an arch or roof, m' . The top of the boiler or boilers will then form the bottom of the chamber h , and will aid in heating the air by radiation from the steam.

I am aware that furnaces in which air is

heated by the products of combustion and conducted to the fire-chamber are not new, and I do not desire to claim the same, broadly.

What I claim as my invention, and desire to secure by Letters Patent, is—

In a boiler-furnace, the combination of a combustion-chamber, and boiler-flues for the passage of the products of combustion which pass under the boiler to the rear thereof and thence through the flues to the front of the boiler, a connecting-chamber, f' , situate at the front of the boiler and communicating with the boiler-flues, a heating-chamber, h , overlying the boiler, a stack, a recurrent flue, $i i'$, arranged in the heating-chamber h , communicating at one end with the chamber f' and at the other end with the stack, an air-adit port in

the heating-chamber h , and a conducting pipe or flue, h^2 , leading from the heating-chamber to the combustion-chamber, whereby the products of combustion passing from the boiler-flues and connecting-chamber f' through the flue $i i'$ into the stack heat the air which enters the air-adit port and circulates around the recurrent flue $i i'$ in the heating-chamber h , finally entering the combustion-chamber 25 through the conducting pipe or flue h^2 , substantially as and for the purposes described.

In testimony whereof I have hereunto set my hand this 2d day of December, A. D. 1884.

JOSEPH ANDERSON.
